UNITED STATES PATENT OFFICE

2,088,465

DYEING APPARATUS

Ernest Clark, Abington, Mass., assignor to Abington Textile Machinery Works, Boston, Mass., a trust of Massachusetts

Application June 22, 1933, Serial No. 676,990

6 Claims. (Cl. 8—18)

This invention relates to beam, package, and tube dyeing systems on the order of that shown in United States Patent No. 836,101, L. Dumons, Nov. 20, 1906, and has as its object the provision of new and improved devices and combinations of parts for performing in improved and simplified manner the necessary steps in dyeing textile fibers when wound as roving or as yarn on the above named carriers.

10 Leading objects of the invention are to provide as far as possible a coordinated and mechanically interlocked arrangement of the flow-controlling valves and their controls so as not only to make easier the manipulation of the many valves involved, but particularly to facilitate or compel their operation in the proper order and timing and from one central operating post, to remove the risk of injury to the stock, and waste of material, always involved in prior systems and resulting from a momentary slip of the operator in failing to work each valve at the proper time and in proper order.

Other objects include the provision of means for oxidizing the dye in the textile material while the dye liquor is in process of being circulated through the system, and for performing a preliminary moisture expelling operation on the material while still in the kier. A further object of the invention is to provide for washing the material while in the kier, with a running wash in which fresh water is presented to the material and thereafter discharged immediately into the waste pipe, without remaining in or returning into contact with the material as heretofore necessitated. Other objects are as will be indicated hereinafter.

To these ends, the invention provides dyeing apparatus in which a dyeing tank or kier and a pump are connected with sources of supply of dye liquor, of washing liquid, and of a gas, through a valve having a single moving part which directs the flow from the pump either from the outside of the wound masses occupying the tank or kier inwardly of such masses, or in the reverse direction, such valve also having a supply-port for the introduction of at least one and preferably all of the aforesaid three fluids. As illustrated, also, the valve has a part formed on it or combined with it which opens or closes the waste or drain pipe to release any fluid passing through the valve into such waste pipe if desired. In the preferred arrangement, compressed air is introduced into the circulating liquor, so that the oxidizing of the dye can in my invention proceed continuously throughout the process. The air

pressure on the wound masses, when applied in the direction to flow from the inside of the wound masses outwardly, which might burst them, is balanced during circulation of the mixture of air and dye liquor by hydraulic and air pressure on the outside of the packages to an extent preventing the building up of pressure differences great enough to rupture the yarns. The system provides for passing air alone through the wound masses to extract the greater part of the moisture following the dyeing operation while the stock is still in the kier, and to prevent bursting of the wound masses under this condition when not protected by hydraulic pressure the air inlet is put on the suction side of the pump, and the valve referred to has its port which directs the flow from the pump to the interior of the wound masses, (to produce a flow outwardly from within the latter,) always in communication with the drain-port, so that if the drain is open, no material amount of air-pressure can be put on the inside of the wound stock, because the air merely passed down the drain; while if the drain-valve be closed, there is no other escape from the system and a static condition is created, with equal pressure at both inside and outside of the wound stock, the air passing through the pump whether running or at rest to effect this equalization. The manner of attaining other aims of the invention will appear as hereinafter.

An illustrative embodiment of the invention is shown in the accompanying drawings, in which,—

Fig. 1 is an elevation of the complete dyeing system or machine.

Fig. 2 is a plan view of certain of the parts of Fig. 1.

Fig. 3 is an elevation of the main and certain auxiliary valves of Figs 1 and 2, together with their connections, on an enlarged scale.

Fig. 4 is an enlarged sectional elevation of the main valve and its controls.

Fig. 5 is an elevation of the rotor of the valve.

Figs. 6 and 7 are horizontal sections of the rotor on lines 6—6 and 7—7, respectively, of Fig. 5, looking in the direction of the arrows.

Fig. 8 is a plan view of the rotor and its rotation-limiting pin.

Fig. 9 is a more or less diagrammatic representation of the various directions of flow in the system.

The improved dyeing system or machine has the usual devices essential to the performance of the operation known in the art as beam dyeing, including a pair of kiers 1 with tight covers 3, to receive the stock to be dyed, a mixing tank 5, a

circulating pump 7, and a motor 9 driving the pump. The valve which forms a leading part of the invention is indicated at 11. A port 13 in the casing 17 of this valve near the top thereof 5 communicates with the side of the kier through pipes 19, 21 and connecting pipe 23, 25, a hand-valve 27 being provided in the connection to one of the kiers, (or to all but one of the kiers, in case more than two are provided,) to render unneeded 10 kiers inoperative. Port 15, near the bottom of the valve-casing 17, is connected by similar piping 29, 31, 33, with the bottom of the kier, a similar hand-operated shut-off valve or valves 35 being provided. It is to be understood that as usual in 15 these systems the connection or pipe, made up of the portions 29, 31, 33, which enters the kier axially at the bottom discharges into the interior of the beam, packages, or tubes, or alternately vents fluids from the said interior of the beams, 20 packages or tubes, and hence delivers the necessary fluids to the kier when the direction of flow is from the interior of these wound masses outwardly through the fibers composing them, and hence is termed the inside-out pipe. Similarly, 25 the pipe or connection between the port 13 and the side of the kier, made up of portions 19, 21, 23, 25, discharges into or vents from the space within the kier surrounding the wound masses, and hence delivers fluids to the kier when the direction of flow is from the outside of such wound 30 masses inwardly to the interior of their porous or hollow carriers, and hence is termed the outside-in pipe.

Port 37 in the valve-casing 17 is connected by 35 pipe 39 with the mixing tank 5, to permit the contents of the latter to be let into the system. Pipe 41 entering the pipe 39 is in communication with a water supply through the pipe 43, a check-valve 45 inserted in the pipe 39 preventing the 40 water from flowing upward into the mixing tank 5, while the feed water to the tank is supplied through pipe 47 under control of hand-valve 49. A valve 51 operated by a stem 53 and a hand-wheel 55 located above the operator's platform 45 or floor 57, controls the admission of water from the main 43 through pipes 41 and 39 into the valve 11 to accomplish the running wash.

A pipe 59 from a source of gas, preferably compressed air, also communicates with the pipe 39 50 attached to port 37, the flow of the air being controlled by valve 61 having its stem 63 also extended above the floor 57 and equipped with a hand-wheel. A check-valve 65 provided in pipe 59 prevents the dye liquor or the water used in 55 the running wash from backing up into the compressed air line or tank in case both valves 51 and 61 are open simultaneously and the air pressure happens to be low.

Thus it will be seen that port 37 by means of 60 pipe 39 supplies the interior of valve 11 with dye liquor, water, or compressed air selectively or simultaneously at option.

At opposite sides of the casing 17, midway of the height of the latter, and 90° away from the 65 port 37 in each direction, there are provided ports 67, 68, connected respectively to the suction side of the pump 7 by pipe 69 and to the discharge side of the pump by pipe 71, a gate valve 73 being located in the latter pipe and controlled from the floor above by shaft 75 and an appropriate hand-wheel.

To the port 71, located in the casing 17 midway between the outside-in port 13 and the inside-out port 15, is attached a line of by-pass piping 75 79 which communicates with the suction pipe 69

of the pump and serves as a by-pass which through its adjustable relief-valve 81, equipped with sprocket and chain control 82, 84, from the operator's platform, controls the maximum fluid pressure allowed to be developed within the kier, 5 thus preventing bursting of the wound masses therein, and regulating the working pressure within the system as needed. From its particular location, the relief valve relieves excess pressure in either direction of dyeing, and hence a 10 single-acting relief valve serves. A strainer, made easily removable for clearing it, is located across pipe 69 at 70, on the pump side of the by-pass pipe 79.

The bottom of the valve casing 17 is closed by 15 a head 83 bolted tightly to the casing, having a port 85 formed as a valve-seat and surrounded by a flange or other means for coupling to a drain-pipe 87, the drain-pipe being adapted to support the weight of the valve 11 and its attached piping, valves, and other associated parts, as by means of the foot 89 on the elbow 91, which foot rests on the floor or abutment 93.

The movable valve member or rotor 95 of the valve 11 comprises the cylindrical body shown in 25 elevation in Fig. 5 and in section in Figs. 6 and 7, as well as in Fig. 4, which latter is a view from the right-hand side of Fig. 3. The rotor has a generally V-shaped channel 97 cut deeply in the surface of its upper half, and carried far enough 30 around the circuit of the rotor so that either upward extremity of the V will just come into full communication with the outside-in port 13 of the casing when the rotor is turned 180°. At the bottom of the V a branch 99 of the channel is 35 carried around the circumference of the rotor clockwise as viewed from above for sufficiently more than 90°, as shown in Fig. 6, so that this branch will be simultaneously in communication with the port 67 connected with the suction pipe 40 69, and with the feed-port 37 through which pipe 39 supplies dye liquor, wash water, and compressed air. Thus when the ports are in the relations of Fig. 4, in which the rotor is in the relation shown in Fig. 5, both the feed-port 37 45 and the outside-in port 13 are in communication with the suction pipe 69 of the pump.

The lower half of the rotor is provided with a similar but inverted V-shaped channel 100 (see 50 Fig. 5) having at its apex a communicating circumferential channel 102 extending clockwise for just enough more than 90° around the circuit of the rotor to be simultaneously in communication with the port 68 into which the pump discharges by means of pipe 71, and also with port 71 of the 55 by-pass 79, so that the discharge from the pump will be directed downwardly through the left-hand branch of the V and out through the inside-out port 15 when the rotor is in the position shown in Fig. 4, and a portion of the flow diverted through the by-pass 79 if necessary in order to reduce the pressure on the goods in the kier.

It is to be noted that the extremities of the inverted V-channel 100 pass vertically downward 65 through the bottom end of the rotor at diametrically-opposite points as indicated by the lines 104, Fig. 5, so that fluids passing through the channel 100 and its branch 102 can pass vertically downward through these vertical passages 70 in the bottom of the rotor upon occasion.

The rotor 95 is mounted within the casing 17 with capacity for rotation back and forth in either direction through an arc of 180° only, this being determined by a stop-pin 106, Figs. 5 and 8, 75

fixed in the cap 108 bolted to and closing the top of the valve-casing 17, the stop-pin bringing up against the ends of a groove 110 cut in the top face of the rotor 95 for the proper portion 5 of the latter's circuit. The stop and groove permit the rotor to move a half turn clockwise from the position shown in Figs. 4 and 5, so that the discharge pipe 11 from the pump and its port 68 are put in communication through the other 10 branch of the upper V-channel 97 with the outside-in port 13, to effect the reversal of the flow of the dye liquor discharged by the pump. The feed-port 37 is cut off from communication 15 with this upper V-channel, and the by-pass port 15 is put into communication with its circumferential branch 99, so that the safety pressure-controlling feature is still effective. By this move, the suction pipe 69 and its port 67 are put in communication through inverted V-channel 100 20 with the bottom inside-out port 15, and the feed-port 37 likewise in communication with the suction side of the pump through the circumferential branch 102 of the channel, so that dye liquor from the mixing tank 5 or water from the mains 25 are properly drawn in to fill the system and keep it full in either position of the valve and in either direction of dyeing.

The rotor 95 is supported within the valve casing by a web 112 having passages 114 registering with the extremities of inverted V-groove 100 which extend through the bottom face of the rotor, when the rotor is in either extreme position permitted by the stop 106. Thus the inverted V-channel 100 is in communication 30 both its extremities through the passages 114 and the communicating space 116 with the port 85 venting into the drain 81. This port 85 is adapted to be closed by a cooperating valve member 118 fixed by nuts 120 on the bottom end of a 35 stem 122 passing through an axial bore 124 in the rotor 9, and in screw-threaded engagement with a hole formed for it in the web 112, so that rotation of the stem by means of the hand-wheel 126 fixed on its upper end above the floor 51 40 serves to move the valve-member 18 vertically toward and from its seat to cut off communication between the system and the drain, or to effect such communication and empty the fluid 45 contents of the system down the drain. The stem 122 is shouldered above its screw-threaded portion and fitted with packing material 128 confined between washers and compressed by jam nuts into sealing engagement with the bore 124.

To work the rotor 95, a sleeve 130 surrounding the stem 122 is fitted tightly within the bore 124 and held from rotation by key 132, the sleeve having fixed on its upper extremity a collar 134 from a socket in which extends a long operating handle 136. A gland 138 in the cap 108 and a 50 packing collar 140 provide for packing the sleeve in the cap.

Steam is provided for heating the fluid contents of the system by means of a pipe 142 coupled to a suitable source and connected through 55 a thermostatic heat control valve 144 with the discharge pipe 11 of the pump, a thermostatic plug 146 located in the suction pipe 69 controlling the action of this valve in known manner. The diagram of Fig. 9 indicates the general directions of flow attainable in the actual dyeing operation, the feathered arrows representing the constant flow to and from the pump 7, the solid lighter arrows the inside-out direction of flow from valve 11 to kier 1 and back, and the dotted arrows the outside-in direction between the valve and the 60 kier. Since the flow to and from the pump

through the respective pipes 69 and 71 is always in one direction irrespective of any reversal of the flow in the kier, namely in the direction of the arrows on these pipes in Figs. 1 and 2, and the feathered arrows of Fig. 9, the thermostatic plug 146 always ascertains the temperature of the dye liquor which is leaving the kier, an obvious advantage. A hand-valve 148 is also provided in the steam line before the thermostatic valve 144, to shut off the steam after the flow of the dye liquor has been completed, and has its stem 150 extended upward above the floor 51 and equipped with a hand-wheel grouped with the other controls about a standard 152 surrounding the sleeve 130 of the main valve 11 15 and the included stem 122 of the drain valve. The standard has a bracket 154 holding an instrument board 156 containing the respective inside-out and outside-in pressure gauges and a gauge recording the temperature within the kier. 20 The usual expansion or vent pipe 158 is provided from the top of the kier to the mixing tank, equipped with hand-valve 160.

With the improved organization described, the ordinary performance of filling the system with 25 water or with dye liquor can be effected through filling the mixing tank 5 by means of the hand-valve 49, or the system can be filled with water alone, by introducing water directly into the piping at full available pressure through the hand-valve 51, pipe 41 and pipe 39 communicating with the main valve 11. This water can be brought to the stock in either direction, or from both directions simultaneously, and if valve 73 be shut and hand valve 160 appropriately opened, 30 with the rotor in either extreme position the stock can be completely wetted out without use of the pump and with corresponding saving of power. Obviously, valve 73 may be in either pipe-line 69 or 11. 35

Thereafter, the usual sequence of operations is carried out to effect the dyeing of the stock, the dye liquor being brought to the proper concentration through additions of the dye to the mixing tank, with observation of the absorption 40 of the dye through the discharge from the vent pipe 158 with hand-valve 160 open, and the appropriate periodic reversal of the direction of flow through the stock accomplished by rotation of the rotor of valve 11. It is to be noted that 45 oxidizing air can be continuously put through the stock along with the dye liquor, so that the oxidation forms a concurrent part of the actual dyeing operation, with known improved results, and is no longer a separate and time-consuming step, 50 the air being allowed to escape freely and continuously from the vent-pipe 158 when and as it frees itself from the emulsion. The usual oxidation following draining-off of the dye-liquor is 55 performed where indicated.

At the completion of this simultaneous dyeing and oxidizing process, the pump and the flow of air are both shut off, hand-valve 160 in the vent pipe shut, and the drain valve at the bottom of valve 11 is opened by lifting valve-member 118 60 from its seat 85 through manipulation of hand-wheel 126, thereby permitting the entire contents of the system to escape down the drain 81, whence it may be either wasted or removed to a suitable place of storage for reuse. It is to be observed 65 that the drain valve which forms a part of the main valve 11 is at the lowest point in the entire system preceding the drain.

On completion of the draining operation, gate valve 73 is closed by means of its shaft 75 ex- 70 75

tending up above the platform 57 to the operator's central control station, the main valve 11 is rotated to outside-in relation as in Fig. 4, and wash water is admitted from the mains through pipes 39, 41, and 43 upon opening valve 51 by means of its hand-wheel 55. This wash water entering the feed-port 37 of main valve 11 is prevented by the closing of valve 13 from short-circuiting through the pump to the drain, and is compelled to travel through the outside-in pipe 19 into the kier to surround the stock therein, entering through the fibers of the stock and leaving the kier through the axial port in the bottom thereof, thence returning through pipe 29 to the valve 11, whence it escapes freely through the still open drain valve in the bottom and leaves through drain pipe 87. This makes a continuous and running wash, as previously referred to. Not only is the operation of the pump and the power thus consumed obviated, but the washing is effected wholly with clean water, which I believe myself to be the first to have accomplished in such a system.

At the completion of the washing operation, drain valve 118 is restored to its seat to close the drain, valve 13 is allowed to remain closed, valve 51 is closed to shut off the water, and with main valve 11 still in outside-in relation the compressed air in pipe 59 is admitted by opening valve 61; it enters the kier through the outside-in pipe, passing through the stock until a static condition is reached with all parts of the system filled with air of the full pressure available. Thereupon, drain valve 118 is lifted widely from its seat, allowing a sudden drop in the pressure between the stock and the drain as a result of the escape of the air down the drain, producing a rush of the remaining air in the system through the stock in the safe outside-in direction, which blows out of the stock and down through the axial port of the kier the greater part of the moisture remaining therein after the washing. Thus there is performed in the kier itself a moisture-extracting operation preliminary to the actual drying operations which must follow, having the effect of greatly shortening the period needed for this subsequent operation.

As to the safety features of the invention, among other such features already indicated, if the operator fails to close valve 13 at any time previous either to the washing or moisture-extracting operation, the only adverse result will be the wasting of the water or the air down the drain, and the stock will not be burst or otherwise injured. If though closing valve 13 properly he fails to open the drain previous to turning on the water or air, no bursting or other harm can result because there is no vent to the system and any harmful inside-out pressure is balanced by an equal and opposed outside-in pressure. If hand valve 160 be wrongly left open, the rush of air is instantly audible. If the main valve 11 be wrongly set for inside-out direction of the fluids, with the drain valve open, these fluids are merely wasted down the drain, and with the drain valve closed the same static relation at both inside and outside surfaces of the stock is attained, before any harmful pressure whatever

can be built up between the inside and the outside of the stock, since the system beyond the outside of the stock is closed.

What I claim is:—

1. In dyeing apparatus, in combination, a dyeing tank, a pump, intermediate conduits, and a reversing valve having at its lowest point a drain port, and a closure means for the latter within the valve casing. 5

2. In dyeing apparatus, in combination, a kier, a pump, intermediate circulation conduits, a reversing valve reversing the direction of flow through the kier, and a relief valve regulating the maximum pressure of the flow from the pump before leaving the reversing valve. 10

3. In dyeing apparatus, in combination, sources of supply of dye liquor, of washing liquid, and of a gas, a dyeing tank, a pump, intermediate conduits joining all these elements, and a valve having a single moving part in the conduits and in conjunction therewith directing the flow from the pump optionally from the outside of the stock occupying the tank inwardly of such stock and also in the reverse direction, the valve also having in addition to its circulating ports a supply port for the introduction of at least one of the aforesaid three fluids, and a by-pass acting to prevent excessive pressures within the apparatus through putting the discharge side of the pump directly in communication with the suction side thereof, before the discharge flow from the pump leaves the valve. 15

4. In dyeing apparatus, in combination, sources of supply of dye liquor, of washing liquid, and of a gas, a dyeing tank, a pump, intermediate conduits joining all these elements, and a valve in the conduits and in conjunction therewith directing the flow from the pump optionally from the outside of the stock occupying the tank inwardly of such stock and also in the reverse direction, the valve also having in addition to its circulating ports a supply port for the introduction of at least one of the aforesaid three fluids, 20 and a drain port in the valve emptying the apparatus and also opened or closed by said valve. 25

5. In dyeing apparatus, in combination, sources of supply of dye liquor, of washing liquid, and of a gas, a dyeing tank, a pump, a pump by-pass, a drain, intermediate conduits joining all these elements, and a valve having ports respectively connected by said conduits to the discharge side and the suction side of the pump, to axial and radial connections to the tank, to the drain, to the by-pass, and to at least one of the said sources of supply. 30

6. In dyeing apparatus, in combination, sources of supply of dye liquor, of washing liquid, and of a gas, a dyeing tank, a pump, a drain, intermediate conduits joining all these elements, and a single manually-operable control-valve 35 having an angularly-movable portion reversing the direction of flow in the tank while receiving and directing the said fluids always into the suction side of the pump, a drain port in the valve connected to the drain, the valve having a member axially movable to empty the contents of the system into the drain. 40

ERNEST CLARK.
